[57] CLAIM

The ornamental design for a kerchief having elastic band, as shown and described.

DESCRIPTION

FIG. 1 is a reduced front left side perspective view of a kerchief having elastic band showing my new design;
FIG. 2 is a top plan view thereof;
FIG. 3 is a front elevational view thereof;
FIG. 4 is a left side elevational view, the right side being the mirror image thereof;
FIG. 5 is a rear elevational view thereof;
FIG. 6 is a bottom plan view thereof;
FIG. 7 is a top plan view of a second embodiment fabricated of an alternate material;
FIG. 8 is a front elevational view of FIG. 7;
FIG. 9 is a left side elevational view of FIG. 7, the right side being a mirror image thereof;
FIG. 10 is a rear elevational view of FIG. 7; and,
FIG. 11 is a bottom plan view of FIG. 7.
